UNITED STATES PATENT OFFICE

SAMUEL F. ARBUCKLE, OF HIGHLAND PARK, MICHIGAN, ASSIGNOR TO MONOGRAM LENS CORPORATION, OF DETROIT, MICHIGAN, A CORPORATION OF DELAWARE

DEPRESSIBLE BEAM HEADLIGHT

Application filed August 1, 1927. Serial No. 209,721.

This invention relates to headlamps and particularly that type of headlamp which is adapted to project at different times two separate beams of light, one for fast driving, and the other for driving in traffic where it is desirable to prevent glare of the headlights in the eyes of drivers of approaching automobiles.

One of the objects of the invention is to provide a headlight having a brilliant beam which may be projected far down the road for fast driving and another beam which may be projected toward the side of the road for driving in traffic or for passing another car.

Another object of the invention is to provide a headlight which will project a substantially white beam down the road for fast driving, and which will project another beam toned down by a color downwardly at a point nearer the car for driving in traffic.

Another object of the invention is to provide a headlight which will project a brilliant beam far down the road for fast driving and another beam for driving in traffic toward the side of the road away from the eyes of approaching drivers while at the same time sufficient light is thrown upon the road near the car to provide adequate illumination.

Still another object of the invention is to provide a headlight which is particularly adapted to driving in rain or mist and which has a depressible beam which will not produce a glare in the eyes of an approaching driver due to reflection from the wet pavement, but which while the depressed beam is used still produces adequate illumination upon the road to enable the driver to clearly see the same.

Other objects of the invention and objects relating to methods and economies of manufacture will be apparent as the description of the invention proceeds.

One embodiment of the invention has been illustrated in the accompanying drawings, in which

Fig. 1 is a sectional vertical elevation of the headlight taken on line 1—1 of Fig. 2 and looking toward the inside of the lens;

Fig. 2 is a sectional horizontal view of the

headlight taken on a line substantially through the center thereof;

Fig. 3 is a sectional side elevation of the headlight taken on a line substantially through the center thereof;

Fig. 4 is an enlarged sectional view and taken on the same plane as Fig. 1; and

Fig. 5 is a sectional view taken similarly to Fig. 2 but showing a modified form of bulb construction.

The invention is shown in connection with the headlight shown and described in my application, Serial No. 203,948, filed July 7th, 1927, and my application, Serial No. 203,950, filed July 7th, 1927, in which a casing 10 is adapted to support a relatively long focal length reflector 11 which has at its center a socket 12 for supporting the light bulb 13. The light bulb 13 has a plurality of filaments 14 and 15 which are adapted to be energized separately by means of suitable connections passing through the socket 12 and not shown in the drawings. As fully explained in my copending applications above referred to, the position of the filaments with respect to the focal length of the reflector may be varied slightly without causing an appreciable variation of the light beam produced, but with the filaments spaced one above the other, two separate beams are produced, the one from the lower filaments being projected far down the road, and the one from the upper filament being projected at a small angle below the first beam, down upon the road whereby danger of glare in the eyes of approaching drivers is avoided.

The said applications also cover the use of a supplementary reflector 16 having a surface substantially in conformation with a portion of a sphere and supported in front of the light bulb 13 by a strip 17 attached near its mid point to the supplementary reflector 16 and having tongues 18 adapted to be inserted into slots in the main reflector 11 at points adjacent the periphery thereof. The reflector 16 intercepts all of the forward direct rays emitted from the filaments and redirects these rays back into the main reflector 11 from which they are projected as an entirely separate beam adjacent to the main

beam. The idea of making the supplementary reflector 16 out of a colored material such as copper, is also brought out in the above referred to applications, whereby the auxiliary beam projected by this reflector is toned down by a reddish brown color and by changing the configuration of the auxiliary reflector, or by changing the reflecting surface as by etching a portion of it, it is shown that the auxiliary beam may be enlarged and made to light up both sides of the road with a diffused and non-glaring light.

Also in the above entitled applications, the use of a lens 19 in combination with the reflector and bulb is shown to produce a desirable result, making possible the use therefor, of a standard two filament bulb in a headlight having a fixed socket, irrespective of tolerances in the manufacture of the bulb. This lens may be held in place in the casing in the usual manner and comprises a pair of flat surfaces 20 and 21, an upper prism 22, a lower prism 23 and a pair of central prisms 24 and 25 arranged in the shape of a trapezoid as is illustrated in Fig. 1 of the drawings. The flat surfaces 20 and 21 of the lens are adapted to permit the light rays to project therethrough without being bent in a vertical direction. This forms the intense part of the beam. The prisms 22, 23, 24 and 25 are adapted to bend the rays passing therethrough downwardly, so that they take a position in the beam of light below the intense portion. The prisms 24 and 25 are placed at that position in the lens where rays are most affected by variations of the filament with respect to the axis of the reflector, and this is also true with the prisms 22 and 23, while the flat portions 20 and 21 project rays which are least vertically affected by variations in the position of the filaments with respect to the focal point of the reflector. The back or inside surface of the reflector is preferably covered with a series of flutes 26 which are formed with a radius, such that the light passing through the lens will be spread to form a pattern of the desired width. The flutes at the back of the upper prisms 22 may be formed with the smallest radius, thereby spreading the light to a large extent while the flutes at the back of the prism 23 may have a longer radius, and those at the back of prisms 24 and 25 and the flat portions 20 and 21 may have a still longer radius.

The above constitutes the invention described and claimed in the applications above referred to, and the present invention contemplates so positioning the bulb that the depressed beam projected by the upper filament is directed toward the side of the road. This is accomplished by fixing the socket 12 in the reflector, so that the upper filament 15 comes slightly to the right of the vertical plane through the axis A of the reflector as seen from a point facing the headlight. This

will throw the depressed beam toward the right side of the road as indicated in Fig. 2, thereby lighting the ditch and crossings at that side and eliminating any danger of light being thrown into the eyes of an approaching driver. The supplementary reflector 16, if formed of copper or colored in such a way that a colored light is produced, will greatly add to the effect of this headlight, inasmuch as that portion of the road directly in front of the car and slightly to the left, will be lighted with a diffused reddish glow so that objects there, may be clearly distinguished. I have found it preferable to locate the lower filament 14 substantially on the vertical plane so that the light projected for the driving beam will be projected straight down the road and not toward the left. This may be accomplished by slightly displacing the bulb with respect to the reflector so that the axis B of the bulb comes slightly to the left of the axial vertical plane A' of the reflector as seen from the rear of the headlight, or it may be accomplished by providing a bulb in which the upper filament is slightly displaced with respect to the axis of the bulb and the arrangement of the positioning pins in the base thereof.

Such a specially constructed bulb is indicated in Fig. 5 wherein a lower filament 14a is provided slightly below the horizontal axis of the bulb and centered upon the vertical axis thereof, while the upper filament 15a is positioned slightly above the horizontal axis of the bulb and to the left of the vertical axis as viewed from the base of the bulb as the section in Fig. 5 is taken. With this construction, the axis B' of the bulb will lie in the vertical axial plane A' of the reflector.

It is evident that upon rotating a standard bulb in the reflector, as indicated in Figs. 1 to 4 inclusive, both upper and lower filaments will be inclined at a slight angle to the horizontal, thus, the beams produced by these filaments will form patterns of light which are tilted with respect to the horizontal. While this tilting of the beam is not noticeable for slight rotations of the bulb with respect to the reflector, if it is desired to throw the depressed beam to the side of the road at a considerable angle, the angular patch of light upon the road especially for the driving beam, may be found objectionable. In this case, the construction shown in Fig. 5 may be used and it will be noted that inasmuch as both filaments are horizontal, there will be no distortion of the beam produced by the lower filament.

In using a depressible beam headlight, from which the lower beam is projected down upon the road, at merely a vertical angle from the driving beam, it has been found that when driving in wet weather, the depressed beam reflecting upon the wet pavement of the road, produces a very objectionable and extremely

dangerous glare directly into the eyes of drivers of approaching cars. The present invention entirely eliminates this objectionable glare, as the depressed beam strikes the road 5 at an angle longitudinally thereof and the reflected light is directed at the same angle toward the side of the road. The light, however, from the auxiliary reflector is thrown, as has been stated, more nearly toward the 10 center of the road, but inasmuch as this light has a reddish tint, it will not reflect to any great extent from the wet pavement, but has a tendency to be absorbed, thereby causing little or no reflection and no glare in the 15 eyes of an approaching driver.

The reddish tint of the light produced by the auxiliary reflector in both the driving and depressed beams, makes the light particularly adapted to penetrate rain, fog or other 20 particles which may be suspended in the air so that the headlight incorporating this invention will provide much greater illumination under adverse weather conditions.

While I have shown the invention in connection with the headlight shown in the two above mentioned applications, it is of course possible to use the invention with any type of headlight. However, I have found that the 25 construction as shown having a reflector, the focal-length of which is not less than ten and one-half, nor more than fifteen times the distance between the filaments, and a compensating lens, provides a much better light, freer from holes for both of the beams than 30 does a headlight, using an ordinary reflector and lens.

While I have shown the filaments positioned above and below the axis of the reflector, the invention is not to be limited to such a placement of the filament, as good 40 results may be obtained with the lower filament at the focal point of the reflector or even slightly above the same.

Only in so far as the invention is particularly pointed out in the accompanying 45 claims is the same to be limited.

Having thus described my invention, what I claim is:

1. In a vehicle lamp, the combination of a parallelizing reflector of long focal length; said reflector having its major reflecting surface located in rear of its focal plane and its forward edge terminating in front of its focal plane, a light bulb having two concentrated separately energizable filaments located substantially in the focal plane of the reflector; means to support the bulb in fixed and non-adjustable relation to the reflector; the lower filament being placed horizontally adjacent the focus and the upper filament being placed substantially horizontally above the axis of the reflector and laterally offset in relation thereto, and a lens having transverse upper, central and lower zones; the upper 55 and lower zones and the middle portion only of the central zone having prisms thereon to deflect light downwardly.
2. In a vehicle lamp, the combination of a parallelizing reflector of long focal length; said reflector having its major reflecting surface located in rear of its focal plane and its forward edge terminating in front of its focal plane, a light bulb having two concentrated separately energizable filaments located substantially in the focal plane of the reflector; means to support the bulb in fixed and non-adjustable relation to the reflector; the lower filament being placed horizontally adjacent the focus and the upper filament being placed substantially horizontally above the axis of the reflector and laterally offset in relation thereto, and means to deflect downwardly the rays issuing from the upper and lower zones of the reflector and the rays issuing from a portion of the central zone of the reflector 70 above and below the bulb.
3. In a vehicle lamp, the combination of a parallelizing reflector of long focal length; said reflector having its major reflecting surface located in rear of its focal plane and its forward edge terminating in front of its focal plane, a light bulb having two concentrated separately energizable filaments located substantially in the focal plane of the reflector; means to support the bulb in fixed and non-adjustable relation to the reflector; the lower filament being placed horizontally adjacent the focus and the upper filament being placed substantially horizontally above the axis of the reflector and laterally offset in 75 relation thereto, a concave supplementary reflector positioned in front of said filaments and having its concave surface opposed with respect to the concave surface of the parallelizing reflector, said supplementary reflector having a different color from that of the parallelizing reflector, and means to deflect downwardly the rays issuing from the upper and lower zones of the parallelizing reflector and the rays issuing from a portion of the 80 central zone of the parallelizing reflector above and below the bulb.
4. A headlight construction comprising a substantially parallelizing reflector having its major portion located behind the focal 90 plane and having a focal length of substantially one and three-fourths inches, a pair of filaments positioned in a vertical plane adjacent the focal plane of the reflector, said filaments being spaced apart approximately nine 95 sixtieths of an inch and each lying substantially in a horizontal plane one above the other, the lower filament being placed adjacent the focal point of the reflector and the upper filament being offset with respect to a 100 plane passing vertically through the axis of the reflector, a supplementary reflector mounted in front of said filaments having a different color from that of the reflector, said supplementary reflector being concave and 105

having its concave surface opposed to that of the main reflector.

5. A headlight construction comprising a substantially parallelizing reflector having its major portion located behind the focal plane and having a focal length of substantially one and three-fourths inches, a pair of filaments positioned adjacent the focal point of the reflector, said filaments each lying in a horizontal plane which planes are spaced apart approximately nine sixty-fourths of an inch, the upper of said filaments being offset with respect to a vertical plane passing through the center of the lower filament, a concave supplementary reflector positioned in front of said filaments and having its concave surface opposed with respect to the concave surface of the parallelizing reflector, said supplementary reflector having a different color from that of the parallelizing reflector, and a compensating lens mounted in front of said filaments and supplementary reflector, said lens having transverse central upper and lower zones, the upper and lower zones having prisms thereon to deflect light downwardly, said lens having a transverse central zone, the side portions of which allow light to pass therethrough without deflection to cast an intense beam of light from the reflector in a substantially horizontal direction.

6. A headlight construction comprising a substantially parallelizing reflector having its major portion located behind the focal plane and having a focal length of substantially one and three-fourths inches, a pair of filaments positioned adjacent the focal point of the reflector, said filaments each lying in a horizontal plane which planes are spaced apart approximately nine sixty-fourths of an inch, the upper of said filaments being offset with respect to a vertical plane passing through the center of the lower filament, a concave supplementary reflector positioned in front of said filaments and having its concave surface opposed with respect to the concave surface of the parallelizing reflector, said supplementary reflector having a different color from that of the parallelizing reflector, and a compensating lens mounted in front of said filaments and supplementary reflector, said lens having transverse central upper and lower zones, the upper and lower zones having prisms thereon to deflect light downwardly, said lens having a transverse central zone, the side portions of which allow light to pass therethrough without deflection to cast an intense beam of light from the reflector in a substantially horizontal direction, said central transverse zone having a prism thereon for deflecting light rays downwardly.

In testimony whereof I affix my signature.
SAMUEL F. ARBUCKLE.
